APPARATUS FOR HANDLING METAL COILS

John W. McMahon and Le Roy Blank, Warren, Calvin H. Windle, Cortland, and David E. Poole, Warren, Ohio, assignors to Republic Steel Corporation, Cleveland, Ohio, a corporation of New Jersey

Application August 8, 1950, Serial No. 178,222

2 Claims. (Cl. 214—8,5)

The present invention relates generally to the art of material handling and is more particularly concerned with a novel method of preparing coils of metal stock for storage or shipment and with novel apparatus implementing that method for handling and transporting said coils in a rapid, efficient manner with a minimum of labor and a maximum of safety and economy.

In the manufacture of steel strip stock, it is necessary, after the stock has been coiled, to strap and oil it preparatory to storage or shipment. These operations necessitate bringing the coils to the strapping station in sequence, strapping them individually, transporting them to the oiling station, oiling them individually, and then transporting the coils to a point where they may be picked up for shipment or storage. Since the coils are normally too heavy for one or two men to lift and carry, apparatus has hitherto been developed to handle the coils in these operations. This apparatus typically includes a ramp on which the coils may be loaded at one end, allowed to run down to a strapping station, then to an oiling station, and finally to a storage or shipment pickup point. This means, however, has not proved to be a satisfactory solution to the problem of handling the coils in this final phase of strip manufacture. For one thing, the labor costs involved in bringing coils to the ramp and taking them therefrom are excessive. In addition, to regulate the travel of the coils in sequence along the ramp and through the strapping and oiling stations and to keep the strapping and oiling operations going properly and efficiently requires a total of at least 4 to 6 men working full time.

In accordance with the present invention, it is possible for the first time, to our knowledge, to operate apparatus of the type described above with not more than 2 men without sacrificing efficiency, production or safety. In fact, the rate of production of the prior art apparatus can be increased substantially through the use of this invention, there being virtually automatic control over coil travel on the ramp to maintain a minimum distance between adjacent coils travelling in sequence through the two final stations. Also, in accordance with this invention, it is not necessary for the operators to handle the coils or even get very close to them, control over the entire operation being accomplished by means of push buttons on a control panel in view of the entire apparatus. Still further, the novel apparatus of this invention may be adapted readily to automatic control means whereby only one operator would be required to assure proper performance of the apparatus and to start and stop the apparatus. Such an operator would be essentially an observer rather than a workman and accordingly would not have to have special strength, skill or training.

Generally, the method of this invention comprises the steps of rolling a coil of metal stock on its periphery along a substantially straight travel course to an intercepting station, intercepting said coil and automatically releasing it after a predetermined interval, rolling said coil on its periphery farther along said course to a strapping station, automatically applying straps to the coil at spaced locations around its circumference, automatically discharging the coil from said strapping station when a predetermined number of said straps have been applied to the coil, rolling said coil farther along said course to an oiling station, automatically oiling the coil, and automatically discharging the coil from said oiling station after a predetermined interval.

A better understanding of this invention and the

way it may be practiced may be had by reference to the drawings which illustrate the preferred embodiment of the invention.

The present novel apparatus will be gained by those skilled in the art upon consideration of the following detailed description, reference being had to the drawings accompanying and forming a part of the specification, in which:

Fig. 1 is a plan view of apparatus embodying this invention in a preferred form;

Fig. 2 is an elevational, sectional view of the apparatus of Fig. 1;

Fig. 3 is a plan view of a coil buggy of this invention incorporated in the Fig. 1 apparatus; and,

Fig. 4 is a wiring diagram showing the electric circuits involved in the operation of said Fig. 1 apparatus.

Generally, the apparatus of this invention comprises a ramp and a pair of spaced entry coil buggies adjacent to one end of it and movable transversely of the ramp, one of these buggies cooperating with the ramp to define an elongated travel course sloping downward from the other buggy. In a preferred embodiment of this invention, however, this apparatus additionally includes a set of delivery coil buggies disposed near the other end of the travel course, one of these delivery buggies cooperating with the ramp to extend the coil travel course to its mate, and means associated with the ramp to intercept coils travelling down it and to stop them and release them at predetermined intervals for further travel individually down the ramp.

With reference specifically to the apparatus illustrated in the foregoing figures, ramp R is made up of a plurality of aligned spaced segments each comprising a floor 10, a stationary side guide wall 11 and an opposed adjustable side guide wall 12. These segments cooperate to define an inclined coil travel course from a point on one side of a conventional coil strapping machine indicated at S and coil oiling apparatus O to the other side of this assembly. Side guide walls 12 are movable transversely of ramp R to accommodate a wide variety of coil widths and are driven in such movement by means including two electric motors. Wall 12 of the upper two segments of ramp R as a unit extends the length of both said segments and is driven by a motor 14 and a cable 13, operatively connecting motor 14 through a speed-reducing unit 16 to a plurality of screws 17 secured to the outer sides of said wall 12. Along the lower end of the ramp, wall 12 is divided into two parts which are similarly driven by a motor 19 through a speed reduction unit 20, a chain 21, and a plurality of screws 22 secured to the outer sides of these two walls 12, as shown in Fig. 1.

Oiling apparatus O and strapping machine S are spaced apart from each other longitudinally of ramp R, machine S being up the ramp from apparatus O and both these devices being disposed adjacent to the ramp and between the opposed ends of walls 12 of adjacent ramp segments. Between the segment ends adjacent to machine S, a pair of cradle rolls 25 are provided and extend transversely of the ramp to receive and support coils as they are strapped.

One of these rolls is driven by a motor 26 so that the coils can be rotated without moving out of alignment with the strapping machine. Another set of cradle rolls 28 are similarly located with respect to oiling apparatus O for the same purpose. Coils are discharged from cradle rolls 25 and 28 by kick-off mechanism, the upper roll in each instance being movable through a vertical arc above the floor of the ramp. A hydraulic piston cylinder 29 serves as the lift means for the kick-off roll of cradle rolls 25, and a similar piston cylinder 30 serves as the lift means for the corresponding roll of cradle rolls 28. Control of the operation of cylinders 29 and 30 may be manual, but preferably is automatic and in timed relation to the strapping machine and oiling apparatus.

Coil intercepting means described and claimed in U. S. Patent 2,485,961 granted October 25, 1949, is disposed immediately up the ramp from machine S, an opening being provided in the ramp floor for the purpose. This means comprises a rocker frame 32 mounted on a stationary shaft 33 for rocking motion endwise of the ramp in response to actuations of a hydraulic piston cylinder 35 connected to frame 32 by means of a piston rod 36 and a link 37 pivoted to a free end of piston rod 36 and to one end of the rocker frame, as shown in Fig. 2.

This free end of the piston rod is also connected pivotally to a second link 38 which extends downwardly and is anchored to a stationary member 40 beneath the ramp to assure proper positioning of link 37 during reciprocation of the piston. In operation, the rocker frame engages the forward edge of a coil C travelling down the ramp toward the strapping machine, as shown in Fig. 2; and after a predetermined interval, rocks on its axis, disengaging the leading edge of coil C and then engaging the back edge of said coil and pushing the coil on down the ramp. Frame 32 then rocks back to its original position as the piston is reciprocated to catch the next coil and hold it until the first coil has cleared the strapping machine, whereupon the second one is immediately released and the cycle repeated. The rocker frame may be operated automatically by suitable conventional means such as an electrical relay system including a timer or equivalent device, as will be understood by those skilled in the art. Alternatively, the rocker may be operated manually by means of a push button control in a similar circuit, the operator pushing the button for each actuation of the piston of cylinder 35.

Adjacent to the upper end of the ramp an entry coil buggy 45 is disposed on flanged tracks 46 extending transversely of the ramp, whereby the buggy may travel across to the ramp to deliver coils thereon in sequence, as will be described. Buggy 45, as illustrated in Fig. 3, comprises a frame 47 mounted on four wheels 48 to run on tracks 46 and has a top surface formed to receive and support a plurality of coils C situated side by side, as shown in Fig. 1. This top surface is curved upwardly away from the direction of coil travel down the ramp whereby the coils carried on the buggy are restrained against travel in the wrong direction. These coils are furthermore restrained against premature travel downwardly of the ramp by means of a guide bar 49 which extends transversely of the ramp adjacent to the upper end thereof and is mounted on a frame 50 which is adjustable to accommodate coils of a wide variety of diameters. The leading end of buggy 45 is formed to define a bridge 52 for alignment with the ramp when the buggy is in its extreme "in" or loaded position, and has an upright stationary side plate 53. Buggy 45 is driven in its travel across the ramp by an electric motor 55 geared in a conventional manner to one or more of wheels 48 and electrically controlled through a push button circuit to be described.

The other entry coil buggy 57 is disposed above buggy 45 and spaced therefrom and is mounted on flanged tracks 58 extending parallel to tracks 46 for travel transversely of the ramps. Buggy 57 comprises a metal frame mounted on four wheels 59 to run on tracks 58 and has an upper surface to engage and support coils C arranged in a group side by side, as shown in Fig. 1, and formed to provide an upwardly sloping portion to engage and restrain the coils carried on the buggy from the travel away from the ramp. As in the case of buggy 45, an adjustable guide bar 60 and frame 61 therefor are provided to support the coils in position on buggy 57 until they are aligned in sequence with the longitudinal axis of the ramp. Frame 61 is suitably the same in construction, mode of operation and effects as frame 50, being adjustable to a wide variety of coil diameters. Buggy 57 is driven by means of an electric motor 63, as described above, control over the operation of this buggy being by means suitably of a push button electric circuit to be described.

Adjacent to the lower end of the ramp and below the oiling machine, a delivery buggy 67 comprising a frame 68 mounted on four wheels 69 to run on a pair of flanged tracks 70 extending transversely of the ramp is provided to receive coils C from the ramp and carry these coils temporarily in batches in side by side relation. Buggy 67 is driven by a motor 71 suitably geared to one of wheels 69 and is supported on frame 68. Frame 68 has a top portion formed to receive the coils and hold them against motion farther down the ramp course, said top portion being recessed longitudinally to the extent that auxiliary means like guide bars 49 and 60 are not required to assure retention of the coils in place on top of the buggy. The trailing end of frame 68 is shaped to define a bridge 72 for the lower ramp portion to receive coils travelling down the ramp and to transmit them to the lower station. A side guide wall 73 extending along one side of bridge 72 serves as an ex-

tension of stationary side guide 11 when buggy 67 is in its extreme "out" or loaded position.

A second delivery buggy 75 is disposed parallel to and spaced just beyond buggy 67. Like buggy 57, this last and lowermost buggy comprises a frame 77 mounted on four wheels 78 and driven by an electric motor 79 through a suitable conventional gearing arrangement for travel transversely of the ramp on flanged rails 80 provided for the purpose. The top portion of frame 77, however, is of different shape than that of frame 68, frame 77 being formed substantially symmetrically, as appears in Fig. 2. But here again, no special auxiliary means such as the guide bar arrangement described above is required to assist in retaining the coils in desired position on buggy 75 until it is desired to remove them for storage or shipment.

Referring now to Fig. 3, it will be apparent how the foregoing apparatus is operated and manually controlled through two independent electric circuits from a control panel on which a number of push buttons are provided to give the operator all the facilities he needs to start, stop and operate the apparatus in any way desired and at practically any rate of production within the limits imposed by the strapping machine and the oiling machine. In tracing out the various circuits, motor 63 which drives buggy 57 is of conventional three-pole, reversible type, and is powered by 220 volt, 3-phase, 60-cycle alternating current. Control of motor 63 is effected through a 250-volt direct current circuit including a push button 100 operatively associated with a conventional solenoid relay 101 to close the gang switch indicated at 105 whereupon motor 63 is driven in a forward direction. A limit switch 106 included in this circuit, automatically opens the circuit when buggy 57 reaches its extreme "in" position and all the coils carried originally thereby have been unloaded onto the ramp. Thus, until switch 106 is reset manually or automatically, motor 63 cannot be connected to drive buggy 57 farther forward when such movement is not physically possible. A second limit switch 107 is provided in the control circuit and opens automatically when buggy 45 is in the extreme "out" position to prevent the delivery of coils from buggy 57 except when bridge 52 is in position to receive and support coils leaving buggy 57. Still another limit switch 108 is provided in a circuit with a second push button 109 which serves to reverse the motor 63. A solenoid relay 110 closes a gang switch 112 in response to impulses resulting from actuation of button 109. Limit switch 108 automatically opens when buggy 57 reaches an extreme "out" position and is ready for forward motion again with a new batch of coils to be processed. Circuit breakers are indicated at 114 while overload relays are shown at 115 and an undervoltage regulator is shown at 117, all to the usual purposes and effects and in conventional relation to each other.

The operating circuit for buggy 45 is basically that for buggy 57 and includes motor 55 like motor 63, and forward and reverse push button controls 120 and 121 with solenoid relays 123 and 124, respectively. A limit switch 126 is provided in this control circuit to open when buggy 45 reaches its extreme "in" position and a second limit switch 127 is provided to open when this buggy reaches its extreme "out" position, to the ends stated above.

The strapping machine drive and strapping machine rolls drive operating circuits are shown next below in the diagram and they include the same general three-wire operating circuits, the strapping machine rolls drive including a motor 130 and the strapping machine drive including a motor 131. The control circuits are also substantially the same as described above, including forward and reverse push buttons 134 and 135 and solenoid relays 137 and 138, respectively, to make the necessary connections in the operating circuits to operate the strapping machine rolls and the machine drive. However, no limit switch means is provided in the strapping machine rolls drive circuit and none is required because there is no counting or timing operation involved. The strapping machine drive on the other hand requires such limit switch means 140 and it is provided, as shown in the diagram and will be readily understood by those skilled in the art.

Motors 142 and 143 are provided to drive the oil pump oiling machine rolls, respectively, and are con-

connected in the aforesaid 220-volt A. C. circuit and controlled in their operation by means provided in the said D. C. circuit, including the usual solenoid and timing mechanisms indicated at 145 and 146, respectively. Limit switches 147 and 148 are provided to operate in response to travel of the two buggies so that when delivery buggies 67 and 75 are in extreme "out" position, the oil pump and oiling machine rolls will be automatically shut off, there being no need for their operation until all the buggies are returned to their starting positions, in which case the limit switches are reset.

Motors 71 and 79 of delivery buggies 67 and 75 disposed at the lower end of the ramp are connected in the said A. C. circuit and are operated by push button mechanisms in the D. C. circuit, as shown in the diagram. As in the entry buggy control circuits, a pair of buttons 150 and 151, respectively, are provided for each of the delivery buggies to enable the operator to advance or withdraw the buggies. The usual limit switch means and solenoid relays as described above, are provided in each of these control circuits so that the buggies will not be driven beyond a predetermined extreme position in either direction.

Motor 14 is also of the three-pole reversing type and is connected in the A. C. circuit to operate side guide 12 of the upper segments of the ramp. The control mechanism for this motor is basically the same as in the foregoing cases and includes a forward push button 154 and a reverse push button 155 connected in the control circuit with solenoid relays 156 and 157, respectively, described above.

The adjustable side guides 12 of the lower two segments of the ramp which are operated by motor 19 connected in the same A. C. circuit are controlled in the movement relative to the opposing guides 11 by means of forward and reverse push buttons 160 and 161 respectively, connected operatively in the said D. C. circuit as described above in reference to motor 14.

The illustrated apparatus is operated typically in generally the following manner. Entry buggies 45 and 57 are each loaded with six strip stock coils disposed side by side and engaged with each other as shown in Fig. 1, guide bars 49 and 60 being manually adjusted according to the diameter of these coils to assure their proper positioning on the buggy frames. The operator then makes the desired adjustment of the adjustable side guides 12 of both the upper and lower ramp sections so that the coils may run down the ramp without undesirable lateral motion, by manipulation of push buttons 154, 155, 160 and 161. The operator then starts buggy 57 on its travel transversely across the upper end of the ramp by pushing button 100. A second push on button 100 results in the clearance of a coil from guide bar 60 and the coil starts down the ramp course, crossing bridge 52 on the way. This coil is intercepted by rocker frame 32 and stopped momentarily and then released for further travel down the ramp to the strapping machine. The operator then starts the strapping machine rolls and the strapping machine unit by pushing control buttons 134 and 135, and when the strapping is accomplished, the coil is automatically discharged from rolls 25 by the kick-off mechanism including cylinder 29 and the coil travels down the ramp to oiling station O. At this point the oil pump and the oiling machine rolls drive are started automatically so that the coil is rotated in contact with the oiling machine brush and is thoroughly covered with oil to protect it in storage or shipment. Through the action of automatic timing mechanism, the coil is kicked-off the oiling machine rolls and travels to delivery buggy 75, crossing bridge 72 provided by the delivery buggy 67 in its extreme "out" position. The operator then pushes one of buttons 151 to move buggy 75 into position to receive the next coil.

The same sequence of operation is carried on until the buggy 57 is unloaded of its coils and buggy 75 is fully loaded with coils. It will be understood, however, that these operations can be carried out with some variation in sequence to suit the convenience of the operator. For instance, he may actuate button 100 several times to deliver several coils in quick succession onto the ramp, as indicated in Fig. 2, so that he may later pay closer attention than he otherwise could, to operations along lower portions of the ramp as each of these coils is going through the various stations.

When there is no longer any need for bridges 52 and

72, the operator starts buggies 45 and 67 on their courses across the ramp and delivers the coils in succession onto the ramp generally as described above. The operations along the course of the ramp at the strapping and oiling machine stations will be the same as in the case of the coils delivered by the first buggy. These operations are continued as described above, each movement of buggy 45 being followed by a substantially equal movement of buggy 67 so that when all of the coils originally on buggy 45 have been discharged onto the ramp and have passed through the stations along the ramp, buggy 67 is disposed to receive the last of them.

In view of the foregoing description of the structure and mode of operation of the illustrated apparatus, it will be apparent that the method of this invention generally described above may take several different forms as set forth in the appended claims. For example, this method may include the steps of delivering a coil to the strapping station, automatically strapping it and discharging the coil from the said station when a predetermined number of straps have been applied to it, next delivering the coil to an oiling station and automatically oiling it, and finally automatically discharging the coil from the oiling station after a predetermined interval. The coils may be delivered one at a time onto the ramp so that there would be no necessity for carrying out the intercepting operation to assure clearance of each coil from the strapping station before the next coil arrives there.

Alternatively, this method may be carried out in the sequence of steps including bringing a plurality of coils onto the ramp and toward the strapping station, intercepting the coils and automatically releasing them in sequence at predetermined intervals to the strapping station, rotating the coils individually on their axes at the strapping station and strapping them as stated above, and finally automatically discharging the coils in sequence from the strapping station when a predetermined number of straps have been applied to them.

Still further, the method may be carried out without performing the strapping operation by automatically oiling the coils individually as they arrive directly from the intercepting station, and finally automatically discharging the coils in sequence from the oiling station at predetermined intervals.

Preferably, however, the method is carried out so that a plurality of coils are brought toward the strapping station, intercepted and automatically released at predetermined intervals to the strapping station, strapped as described above, and automatically discharged in sequence, then oiled in sequence at an oiling station, and finally automatically discharged from the oiling station in sequence at predetermined intervals.

Having thus described the present invention so that those skilled in the art will be able to gain a better understanding and practice the same, we state that what we desire to secure by Letters Patent is defined in what is claimed.

What is claimed is:

1. Apparatus for handling coils of metal stock comprising a ramp, a stationary side guide wall extending lengthwise along one side of the ramp, a laterally movable side guide wall extending lengthwise adjacent to the other side of the ramp, a pair of coil buggies adjacent to one end of said ramp, one of said buggies having a bridge portion cooperating with the ramp to define an elongated inclined coil travel course, and adjustable coil guide bars adjacent to an extending lengthwise of said buggies and having end portions adjacent to one of said side guide walls to engage and support coils carried by the buggies prior to their delivery onto the ramp by said buggies.

2. Apparatus for handling coils of metal stock comprising a ramp, a stationary side guide wall extending lengthwise along one side of the ramp, a laterally movable side guide wall extending lengthwise adjacent to the other side of the ramp, a pair of coil buggies adjacent to the upper end of said ramp, and a pair of coil buggies adjacent to the lower end of said ramp, the inner member of each pair of buggies having a bridge portion cooperating with the ramp to define an elongated inclined coil travel course, and adjustable coil guide bars adjacent to and extending lengthwise of the buggies adjacent to the upper end of the ramp and having end portions adjacent one of said side guide walls to engage and sup-

port coils carried by the buggies prior to their delivery onto the ramp by said buggies.
